NECKTIE FOR AN OPEN-COLLAR SHIRT

H. Heath Webb, 216 Applewood Lane,
Virginia Beach, Va. 23452

Filed Nov. 6, 1973, Ser. No. 413,240

Term of patent 14 years

Inc. Cl. D2—05

U.S. Cl. D2—351

FIG. 2

FIG. 1 is an elevational view of a necktie for an open-collar shirt showing my new design; and

FIG. 2 is an elevational view of another embodiment of the design of FIG. 1.

I claim:

The ornamental design for a necktie for an open-collar shirt, as shown and described.
